UNITED STATES PATENT OFFICE.

JOHN C. LINDNER, OF ROCHESTER, NEW YORK, ASSIGNOR TO GENERAL RAILWAY SIGNAL COMPANY, OF ROCHESTER, NEW YORK.

INTERLOCKING SYSTEM FOR RAILROADS.

Application filed February 23, 1926. Serial No. 89,886.

This invention relates to an interlocking system for railroads, and more particularly to cross-protection means for electrically operated traffic controlling devices and to systems wherein two electrically operated traffic controlling devices may be controlled by a single lever including such cross-protection means.

The principle of cross-protection upon which the present invention is based, resides in the provision of an electro-responsive cross-protection device which is so connected in the circuit arrangement that, if current is improperly applied to the traffic controlling device, such unauthorized current will pass through the cross-protection device and in so doing will operate it and cut off all electrical energy. More specifically, in accordance with the present invention it is proposed to employ a control circuit in which the cross-protection device is contained, and to provide means for shunting the cross-protection device at such times when current may flow which should not operate the cross-protection device.

In the installation of interlocking systems it is quite common for two traffic controlling devices, either switches or signals, to be so located that they must always be operated at substantially the same time, and a large saving in interlocking equipment, as well as lever space in the interlocking machine, may be taken advantage of, if such devices are operated from the same lever. For such cases, it is proposed to provide a special arrangement of indication circuits and devices so that both traffic controlling devices must respond to the operation of the lever before the indication is effective.

Other objects, purposes and characteristic features of the invention will appear as the description thereof progresses.

In describing the invention in detail reference will be made to the accompanying drawings in which:

Fig. 1 shows a simple application of the cross-protection arrangement embodying the present invention applied to a lever controlling a light signal; and

Fig. 2 illustrates an interlocking system with a single lever controlling two switch machines at a cross-over, and employing the cross-protection features of the present invention.

Referring to Fig. 1, the lever L of the usual construction is shown in a simplified and diagrammatic manner for controlling a two-indication light signal Z by governing its control relay K. The lever L is shown in its normal position, and the control relay K is de-energized, lighting the red lamp R from a source of current 2 by a circuit through a back contact of said relay.

In order to clearly understand the manner in which the control relay K is protected against operation due to the flow of unauthorized currents, let us consider the various circuit changes and operating functions which take place when the signal Z is controlled by the lever L. Let us first assume that the lever L is moved from right to left from the normal position to the reverse position. During the first portion of this stroke, namely when the lever is moved to the indicating position, an indicating circuit is completed through the contacts 3—4 of the lever and the back contact 5 of the control relay K. This circuit is, however, unimportant at this time, because the lever is being moved from right to left and the condition of the indication magnet IM is not important.

When the lever has reached its extreme left hand or reverse position, the contacts 6—7 of the lever shunt the cross-protection relay CR; and the contacts 4—8 complete an energizing circuit for the control relay K which may be traced as follows:—beginning at the battery 10, wires 11 and 12, contacts 4—8 of the lever L, wire 13, winding of the control relay K, wires 14 and 15, contacts 6—7 of the lever, wires 16 and 17, contacts 18 of the cross-protection relay CR, and common return wire 19 leading to the other side of the battery 10.

With this circuit completed, the control relay K is energized, thus closing an energizing circuit for the clear or proceed lamp G. It should be noted, that the circuit just traced includes the connections leading to the winding of the cross-protection relay CR but that this winding is shunted by shunting wires 15 and 16 and shunting contacts 6—7, so that the cross-protection relay CR is not operated. It should also be noted that a break anywhere in this circuit except in the coil of the cross-protection relay is on the side of safety.

Let us now assume that the operator desires to move the lever L to its normal position, in order to unlock certain conflicting routes,

In accordance with interlocking practice there should be assurance that control relay K has assumed its de-energized position before the lever L can be moved to the full normal position. As the operator moves the lever from left to right, he breaks the energizing circuit for the control relay K, and also the shunt around the cross-protection relay CR. As the lever is moved from the left to right it cannot be moved beyond the indicating position because the indication magnet IM is de-energized and causes the plunger 22 to engage the projection 23 on the lever L, so that the lever cannot be moved to the normal position so long as the indication magnet IM is de-energized. In the indicating position of the lever L the contacts 3-4, however, complete an indication circuit including the indication magnet IM providing the control relay K has reached its de-energized position, which indication circuit may be traced as follows:—beginning at battery 10, wires 11 and 24, back contact 5 of the control relay K, wire 25, contacts 3-4 of the lever L, wire 26, winding of the indication magnet IM, wire 27, contact 18 of the cross-protection relay CR, common return wire 19 back to battery 10. With this circuit completed the lever is unlocked and the operator may move to its normal position, in which position the conflicting levers heretofore mentioned are unlocked.

In order to illustrate the manner in which the cross-protection relay CR prevents the flow of unauthorized current from energizing the control relay K, let us assume that the wire 13 is accidentally, due to a cross or the like, connected to the positive terminal of battery 10. Current to energize the control relay K must pass through the cross-protection relay CR in order to complete a circuit to the battery 10; and this current energizes the cross-protection relay, thereby lifting the latch 28 and opening of contacts 18, to cut off the battery 10. The contacts 18 remain open until manually restored in some suitable manner. According to recognized practice, this restoring means, not shown, would be of such a type that it could not be used to keep the contacts 18 closed.

Fig. 1 thus illustrates a simple embodiment of the invention, the principle of which resides in the inclusion of a cross-protection relay in a proceed circuit and in preventing this cross-protection relay from being operated at a time when the lever is in a position to energize such proceed circuit, by shunting the cross-protection device at the critical time it is desired to energize the proceed circuit. The cross-protection relay at other times is connected in series with such proceed circuit, and if unauthorized energy is applied to the proceed circuit it will cause actuation of the cross-protection device, and the main return wire leading to such source of energy is entirely cut off.

Although Fig. 1 illustrates a two unit light signal controlled by a control relay K, it is of course to be understood that the control relay and signal merely represent an electro-responsive device which, if energized, indicates proceed, and that any suitable type of signal or other traffic controlling device may be used.

In Fig. 2 of the drawings has been shown a circuit arrangement in an interlocking system for controlling two switch machines by the same lever and for reliably receiving an indication only if both switch machines have responded to a change in the position of such lever. In order to simplify the description of the operation of the system shown in Fig. 2, the essential mechanisms will first be briefly described, after which the operation of the system will be considered in detail.

Referring to Fig. 2, the lever L¹ illustrates one lever of an interlocking system in which a plurality of levers are mechanically or electro-mechanically interlocked, in a manner so that conflicting routes cannot be set up. This lever L¹ is provided with an indication magnet IM¹ which, if deenergized, will prevent the lever L¹ from being moved from the half normal to the full normal, or from the half reverse to the full reverse positions respectively. A lock magnet LM, if deenergized, locks the lever in the full normal or the full reverse position as the case may be. This lever L¹ is also provided with a double throw push button contact 30, whereby only one or the other, either the indication magnet IM¹ or lock magnet LM may be selected at a time, this contact being operated by the push button 31. This lever L¹ has been shown in its normal position in which the switch machines SM¹ and SM² are in the main line position. If the lever L¹ is moved to the reverse position, the switches S¹ and S² assume the cross-over position so that a train may cross from the lower east bound track to the upper west bound track, or vice versa. The apparatus in the tower, illustrated by the dotted rectangle 29, also includes a cross-protection relay CR¹, an indication relay IR, and an indication selector IS.

The mechanism of the switch machine SM¹ and switch machine SM² is shown in dotted rectangles. The block in which the switch machine SM¹ of the west bound track is contained, includes a track relay T¹, whereas the block of the east bound track, in which the switch machine SM² is located, is provided with a track relay T². In order to simplify the specification, the mechanism associated with one of the switch machines only will be described, and corresponding parts of the two switch machines will be designated by reference characters having exponents "1" and "2" respectively. The switch machine SM¹ includes a motor, having an armature 40¹ and a series field winding 41¹, which motor through a suitable throw bar may operate

the switch S^1 . This switch machine SM^1 also includes movable contact blocks 42^1 and 43^1 . The block 42^1 contains segments 44^1 and 45^1 for reversing the motor when it has reached the end of its operating stroke, and this block 42^1 is operated by snap action near the end of the stroke of the switch machine. The block 43^1 is provided with segments 48^1 and 49^1 and connects one or the other of the 10 pole changing coils 46^1 or 47^1 in multiple with the switch machine motor when the switch machine assumes a corresponding extreme position, but makes the necessary connection for both of these pole changing coils 15 when the switch machine is at any other than an extreme position, for causing the reversing switch contact block 42^1 to assume a position to cause the motor to operate in the proper direction when the normal or reverse 20 circuits are energized, the block 43^1 being operated intermittently to obtain this function.

In other words, if the switch machine SM^1 should assume an intermediate position and 25 current should be applied to the normal wire 123, current would flow through the pole changer coil 47^1 thereby causing attraction of an armature (not shown) associated with the contact block 42^1 , so as to move this block 30 toward the left to effect a connection between the armature 40^1 and field 41^1 , such as to cause the motor to operate the switch machine toward the normal position. In a similar way 35 the application of current to the reverse wire 77 causes the pole changer coils 46^1 to establish the proper connections for the motor to cause it to operate the switch machine SM^1 toward the reverse position. For reasons 40 already given, one of these pole changer coils is disconnected when the switch machine has reached an extreme position after operation 45 from a neutral position as just explained. For a more detailed description of these switch machines reference may be had to the patent to Howe #1,466,903 September 4, 1923.

Contained in the mechanism casing of the switch machine SM^1 , or in a separate casing as is desired, are switch box contacts for completing indication circuits when both switch machines assume corresponding positions. These switch box contacts include a movable contact block 50^1 having contact segments 51^1 , 52^1 , 53^1 and 54^1 . This contact block 50¹ is operated in accordance with the movement of the switch points and is shown in the normal main track position of the switch machine SM^1 .

Operation of Fig. 2.

Let us assume that the blocks of the west bound and east bound tracks in which the switch machines SM^1 and SM^2 are located are unoccupied, so that the track relays T^1 and T^2 are energized, and that the operator de-

sires to set up the track for a cross-over move. In order to do so he operates the push button 31, whereupon the lock magnet is energized through the following circuit:—beginning at the terminal B of a suitable source of energy, push button contact 30 of the lever L^1 , contact 60, wire 61, winding of the lock magnet LM , wire 62, front contact 63 of the track relay T^2 , wire 64, front contact 65 of the track relay T^1 , wire 66 and common return 70 wire C connected to the other side of said source of energy.

With this circuit completed, the lock magnet LM assumes the energized position and the plunger 67 is raised out of engagement 80 with the projecting portion of the lever L^1 , so that the operator is now free to move the lever to the half reverse position where it is stopped by engagement of the lock plunger 68 of the indication magnet IM^1 with the end 85 of the notch cut in the bottom portion of the lever L^1 .

With the lever in this the half reverse position, an energizing circuit for the motor is completed which may be traced as follows:— 90 beginning at the secondary winding of the transformer 70, wires 71, 72 and 73, contacts 74—75, wire 76, “reverse wire” 77 through the motors and fields of the two switch machines in multiple, wires 78, 79 and 80, contacts 81—82 of the lever when the lever is in the half reverse position, wires 83 and 84, contacts 85 of the cross-protection relay CR^1 , wire 86 back to the other terminal of the secondary winding of transformer 70. 100

With this circuit completed, the two switch machines will be operated to the reverse position, thus causing the motor reversing contact blocks 42^1 and 42^2 to be moved to the opposite position by snap action, thereby cutting energy off of the motors 105 of these switch machines.

With the switch machines in the reverse position, all of the various contact blocks 42^1 , 43^1 , 50^1 , 42^2 , 43^2 and 50^2 will assume the 110 lefthand position; and with the lever in the half reverse or full reverse indicating position, an indication circuit for the indication relay IR is completed which may be traced as follows:—beginning at the secondary winding of the transformer 90, wires 91 and 92, contacts 93²—51², wires 94, 95 and 96, contacts 93¹—51¹, wires 97 and 98, winding of the indication relay IR , wire 99, contacts 100¹—54¹, wire 101, contacts 102¹—52¹, wires 103 and 104, contacts 100²—54², wires 106 and 107, contacts 102²—52², wires 108 and 109, back to the secondary winding of the 115 transformer 90. 120

It should be noted that this circuit was traced from left to right through the indication relay IR , which is a three-position alternating current relay having local winding 110 normally energized by current having the proper phase relation to cause this relay to 125 130

assume its left hand dotted position. With the indication relay IR energized to its left hand position, an indication circuit through the indication magnet IM¹ is completed 5 which may be traced as follows:—beginning at the terminal B of a suitable source of energy, push button contact 30, stationary contact 32, wire 33, winding of the indication magnet IM¹, wire 34, contacts 35—36—37 of the indication selector IS (this indication selector having been operated to this position when the left hand indication selector coil was energized by the current flowing to the switch machines when the switch machines 10 were operated to the reverse position), wire 38, contacts 39—56 of the lever, wire 57, contact 58 of the indication relay IR when in the left hand position, wire 59 to common return wire C connected to the other side of said 15 source of energy.

With this circuit completed, and with the indication magnet IM¹ energized, the operator is free to complete the movement of the lever to the full left hand or reverse position, 20 in which position certain other levers are locked or unlocked as conditions require.

From the tracing of the circuit for the indication relay IR heretofore traced it readily appears that such indication circuit would 25 not have been completed had one of the switch machines failed to respond to the change in the position of the lever, so that the lever could not have been moved to the full reverse position unless both of the switch machines had properly responded.

Let us now assume that a train has passed over the cross-over, and that the operator in the tower wishes to restore the switches S¹ and S² to their normal position. For reasons heretofore given, this cannot be done 30 until the blocks, in which the switches S¹ and S² are located, are unoccupied, because the lever L¹ is locked by the lock magnet LM so long as either the track relay T¹ or the track 35 relay T² is de-energized. If the track relays T¹ and T² are energized, depression of the push button 31 releases the lock magnet LM, permitting the operator to move the handle from left to right until the end of the recess 40 in the bottom of the lever L¹ engages the plunger 68 of the indication magnet IM¹. In this the half normal position of the lever L¹ an operating circuit for the two switch machines is completed which may be traced as 45 follows:—beginning at the second winding of the transformer 70, wires 71 and 120, the right hand winding of the indication selector IS, wire 121, contacts 75—122 of the lever L in its half normal position, “normal wire” 50 123 through the two switch machine motors which now have their armatures and field connected to cause operation of the switch machine toward the normal main track position, wires 78, 79, 80 and 124, contacts 82—125 of the lever closed when the lever is in the

half normal position, wires 126, 83 and 84, contacts 85 of the cross-protection relay CR¹, wire 86 back to the secondary winding of the transformer 70.

With this circuit completed, the indication selector IS is operated to its right hand position (in which it has been shown), and also these switch machines will operate the switches and the contact blocks to the normal position (in which they are shown). Under 75 this condition of the apparatus, an indication circuit for the indication relay IR is completed which may be traced as follows:—beginning at the secondary winding of the transformer 90, wires 91 and 130, contacts 80 52²—131², wires 106 and 132, contacts 131¹—52¹, wires 133 and 99, winding of the indication relay IR, wire 98, contacts 53¹—134¹, wires 135, 101 and 136, contacts 51¹—137¹, wires 138 and 104, contacts 85 53²—134², wire 95, contacts 51²—137², wires 139 and 109 back to secondary winding of transformer 90.

It should be noted that the circuit through the indication relay IR just traced was traced 90 from right to left through the winding of the relay IR but was started from the same terminal of the transformer 90 as when the reverse indication circuit was traced heretofore, from which it readily appears that the 95 indication magnet IR is energized to the opposite position from what it was when the switch machines were moved to their reverse position, and will, therefore, assume the right hand or normal position shown. With the 100 indication relay IR in the normal position, the indication selector in the normal position, for reasons just given, and with the lever L in the half normal position, a circuit for the indication magnet IM¹ is completed 105 which may be traced as follows: beginning at the terminal B of a suitable source of energy, push button 30, stationary contact 32, wire 33, winding of the indication magnet IM¹, wire 34, contacts 35—36—140 of 110 the lever, wire 141, indication contacts 39—142, wire 143, contact 58 of the indication relay IR in its normal position, wire 59 to common return wire C connected to the other side of said source of energy.

With this circuit completed, the indication magnet IM¹ moves its armature and plunger 68 to the lower position against the force of compression spring 144, whereupon the operator is free to complete the movement of his lever to its full right hand normal position.

It should be noted that the circuit for the indication magnet IM¹ cannot be completed 125 unless the lever is in a half normal or half reverse position, and the indication relay IR and the indication selector IS are in corresponding positions. This gives additional protection because the circuit for the indication magnet cannot be completed unless 130

each of the various devices have properly responded. Also, the indication magnet IM^1 is very quick acting, so that it will assume its locked position before the operator, by a quick move, can move the lever from one indication to the other indication position. This precaution is taken to avoid accidental or malicious movement of the lever beyond a particular indication position without requiring both switch machines to first assume a corresponding position.

In connection with the circuits for the indication relay IR heretofore traced it should be noted that the winding of the indication relay IR is short circuited, or shunted, through shunting contacts 54^1 — 100^1 and contacts 53^1 — 134^1 in series when the switch machine SM^1 is in an intermediate position; and further that the wires 96 and 103, through which the indication circuit was traced when the switch machines were moved to the reverse position, are shunted by shunting contacts 53^2 — 134^2 , and that the wires 132 and 138, through which the indication circuit was traced when the switch machines were moved to their normal position, are shunted by contacts 54^2 — 100^2 when the switch machines S are in an intermediate position. From this it appears that the two indication circuits heretofore traced in connection with the indication relay IR are bridged or shunted at one point at least, when one or the other switch machine has not yet assumed an extreme position. These circuits are shunted at two places if both machines have not reached an extreme position, and both circuits are interrupted at a plurality of points so long as one or the other switch machine is at an intermediate point in its stroke. Further, it should be noted that the presence and proper functioning of stationary shunting contacts 100^1 — 134^1 — 100^2 — 134^2 are all checked each time the switch machine is moved to the reverse position and is moved back to its normal position, because an essential portion of the indication circuit includes these contacts at one time or the other. Hence, if these shunting contacts, which are essential to assure proper shunting of the indication relay IR at certain times, are broken, bent up or are burnt away due to arcing, no indication can be received, and such contacts must be replaced before further operation of the switch is possible, so that it is assured that these shunting contacts are in proper working condition at all times. Further, the cross-protection relay CR^1 is contained in, but shunted, in each of the operating circuits for switch machines SM^1 and SM^2 under operation thereof in either direction, that is, when the lever is in one or the other indication position; and this cross-protection relay CR^1 is left unshunted in such circuits when the lever is in either of the two extreme positions. Hence, if energy should be applied to the normal wire

while the lever is in the reverse position, or to the reverse wire while the lever is in the normal position, this current will also traverse the cross-protection relay CR^1 , and cause its operation, thus cutting off all available energy for operating the switch machine. The net result is that the energy will be cut off before the switch machines will start to operate, thus assuring adequate cross-protection.

Having thus shown and described several systems in which various phases of the present invention have been shown applied, it should be understood that the particular embodiments of the invention selected are not intended to illustrate all of the constructions preferably employed in practice, nor the scope of the invention, and that various additions, changes and modifications may be made to adapt the construction to the problems and systems encountered in practice, without departing from the scope of the invention, or the idea of means underlying the same.

What I claim as new is:—

1. In an interlocking system, the combination with two switch machines, an indication relay, a source of energy, and of two circuit controlling devices each controlled separately by one of said switch machines for connecting said source of energy to said relay to indicate when both switch machines assume corresponding positions, said circuit controlling devices being so connected in a circuit arrangement that the partial circuit leading to said indication device is shunted by shunting contacts when either of said switch machines assume an intermediate position and when one switch machine assumes one extreme position and the other switch machine assumes the other extreme position, said shunting contacts forming part of the indication circuits, whereby the working condition as well as the presence of said shunting contacts is checked each time the switch machines are operated to the reverse position and back to normal.

2. In an interlocking system, the combination with a lever of an interlocking machine, of an electrically operated traffic controlling device, a circuit controlled by contacts on said lever closed when said lever is in the half or indicating position for operating said traffic controlling device to a certain position, said circuit including a cross-protection device which if operated cuts energy off of said system but which cross-protection device is shunted by contacts on said lever closed only when said lever is in said half or indicating position, whereby if said lever is moved to the full position said cross-protection device is left unshunted in said circuit.

3. An interlocking system comprising, a lever interlocked with a plurality of other levers so that certain of said other levers cannot be operated unless said lever assumes a

- certain position, a traffic controlling device, a source of electrical energy, a cross-protection device which if operated disconnects said source of energy from the system, contacts on said lever closed when said lever is in the indicating position for operating said traffic controlling device by energy derived from said source through a circuit including said cross-protection device, and other contacts 5 for shunting said cross-protection relay on said lever and closed when said lever is in said indicating position, whereby said cross-protection device is left unshunted in the circuit of said traffic controlling device when said lever is in either extreme position, so that the application of unauthorized current thereto effects operation of said cross-protection device before said traffic controlled device responds to such unauthorized current.
- 20 4. An interlocking system comprising, a lever interlocked with a plurality of other levers so that certain of said levers cannot be moved unless said lever assumes a predetermined position, an electrically operated traffic controlling device, an electrically operated cross-protection device connected in series with said traffic controlling device, a source of energy connected to said system through contacts of said cross-protection device which 25 contacts are open if said cross-protection device is in its operated position, contacts associated with said lever for applying current to said traffic controlling device when the lever is in a certain position, and other contacts associated with said lever for shunting said 30 cross-protection device when the lever is in said certain position, whereby said cross-protection device is not operated upon the application of current to said traffic controlling device by said lever but is left unshunted in series with said traffic controlling device at other times and is operated if unauthorized current is applied to said traffic controlling device at times when said lever is not in 35 position to operate said traffic controlling device.
5. Traffic controlling apparatus comprising, a traffic controlling device controllable from a source of energy, a cross-protection device having its operating coil connected in series with said traffic controlling device and which if operated prevents said traffic controlling device from being operated by current from said source of energy, and a lever 40 for simultaneously applying current from said source to said traffic controlling device and shunting the coil of said cross-protection device.
- 45 6. In a control system for controlling two switch machines by the same lever, the combination with a lever having a normal and a reverse position, two switch machines connected in multiple to normal and reverse wires respectively leading to said lever, an indication selector operated to one position

when current flows in said normal wire and to the other position when current flows in said reverse wire, a three-position indication relay in a circuit including a source of energy and circuit controls operated by said switch machines in a manner to cause said relay to assume one energized position only if both switch machines assume one extreme position and cause it to assume the other energized position only if both switch machines 70 assume the other extreme position, an indication magnet for said lever which if energized permits said lever to be moved to the normal or to the reverse position, and a circuit for energizing said indication magnet 75 closed only if said lever, said indication selector and said indication relay all assume corresponding positions.

7. In a control system for controlling two switch machines with the same lever, the combination with a lever having a normal and a reverse position, a source of energy, two switch machines each having a normal and a reverse wire and connected in multiple and to said lever in a manner so as to connect the 80 normal wires to said source of energy when the lever is normal and connect the reverse wires to said source of energy when the lever is reversed, an indication selector operated to one position when current flows in said 85 normal wire and to the other position when current flows in said reverse wire and which remains in its last operated position, an indication magnet for said lever preventing 90 said lever from being moved to either the normal or the reverse position when de-energized, and means for energizing said indication magnet effective only if said lever, said indication selector and both of said switch machines 95 assume corresponding positions. 100

8. The method of protecting by cross-protection relay an interlocking system for railways of the type wherein a distant traffic controlling device is at times operated from a local source of current which has one terminal thereof connected directly to a line wire returning to such traffic controlling device, which consists in connecting the winding and a normally closed contact of such cross-protection relay in said line wire, and in shunting 110 said winding only when current should be flowing in said line wire, whereby if current from said source is caused to flow in said line wire through an unauthorized partial circuit when no current should flow therein 115 said cross-protection relay is operated and said line wire is disconnected from said source of current. 120

9. In an interlocking system comprising; an electrically operated traffic controlling device; a circuit for operating said device including a source of current, the winding and a normally closed contact of a cross-protection relay, and a normally open contact of a manually operable interlocking lever; a con- 125

tact on said lever for shunting the winding of said cross-protection relay closed when said normally open contact is closed; and indicating means having an indicating circuit including a normally closed contact of said cross protection relay.

10. In an interlocking system comprising; an electrically operated traffic controlling device; a circuit for operating said device including a source of current, the winding and a normally closed contact of a cross-protection relay, and a normally open contact of a manually operable interlocking lever; and a contact on said lever for shunting the winding of said cross-protection relay closed when said normally open contact is closed.

11. In a control system for controlling two switch machines by the same lever, the combination with a lever having a normal and a reverse position, a source of energy, two switch machines each having a normal and a reverse wire connected in multiple and to said lever in a manner so as to connect the normal wires to said source of energy when the lever is normal and connect the reverse wires to said source of energy when the lever is reversed, a cross-protection relay at all

times having its winding connected in a circuit portion in series with said source of energy, and means for shunting said winding when current is caused to flow in either said normal or said reverse wires due to operation of said lever.

12. In an interlocking system for railways, the combination with a lever interlocked with other levers of such system, a lock magnet having its energization controlled in accordance with traffic conditions for locking said lever in either of its extreme positions, an indication magnet controlled by indication current flowing when the traffic controlling device controlled by said lever has responded to a change in the position of said lever for locking said lever against movement from an intermediate to such extreme position, and manually operable means associated with said lever which if in one position opens the circuit for said lock magnet and in the other position opens the circuit for said indication magnet, whereby a quick stroke of said lever from one extreme position to the other extreme position cannot be made.

In testimony whereof I affix my signature.
JOHN C. LINDNER.
